Primary Examiner — Jack Reickel*Assistant Examiner* — Salamah Jordan(74) *Attorney, Agent, or Firm* — Bateman IP; Randall B. Bateman(57) **CLAIM**

I claim the ornamental design for an exercise bench, substantially as shown and described.

DESCRIPTION

FIG. 1 is a front perspective view of an exercise bench showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed lines in the drawings are use for structures to place the invention in context, but do not form part of the claim.
